DESIGN FOR A PROJECTOR

Max Levey, Chicago, Ill., assignor to Excel Projector Corp., Chicago, Ill., a corporation of Illinois

Application October 1, 1937, Serial No. 71,921

Term of patent 7 years

To all whom it may concern:

Be it known that I, Max Levey, a citizen of the United States, residing at Chicago, in the county of Cook and State of Illinois, have invented a new, original, and ornamental Design for a Projector, of which the following is a specification; reference being had to the accompanying drawing, forming a part thereof.

In the drawing:

Figs. 1 and 2 are opposite side elevations of the projector;

Fig. 3 is a front end elevation; and

Fig. 4 is a top plan view.

I claim:

The ornamental design for a projector, as shown.

MAX LEVEY.
